METHOD AND APPARATUS FOR VENTILATING LABORATORY FUME HOODS

Walter W. Kennedy, Rockford, Ill., assignor to Barber-Colman Company, Rockford, Ill., a corporation of Illinois

Filed Feb. 19, 1958, Ser. No. 716,091
4 Claims. (Cl. 98—115)

The present invention relates to fume hoods for laboratory tables and the like, and more particularly, to a method and apparatus for ventilating a hood of this type.

Laboratory fume hoods are conventionally employed to exhaust noxious or otherwise unwanted gases from work areas. Normally, the hood surrounds all but one side of the area so as to leave an open face affording access for the technician. The hood exhaust system draws in air through the open hood face and thus continuously sweeps the area of objectionable gases, preventing escape of the gases into the room. Experience has dictated that the air velocity through the work region should not exceed 100 feet per minute so as not to blow out burner flames, disturb chemicals of a fluffy nature, or affect the operation of delicate equipment.

The continuous intake of air by the fume hood and its exhaust system presents a serious problem when the room in which the hood is located is heated or cooled for the comfort of laboratory personnel. In a typical hood installation, where the open hood face measures 32 square feet and the air intake velocity is held at 100 feet per minute, 3200 cubic feet of room air per minute is lost. To successfully air-condition a laboratory having a single hood, an eight-ton unit would be required merely to compensate for the cooled, conditioned air which is lost. A corresponding loss of heated air would occur in the winter season.

In order to avoid this loss while maintaining comfortable conditions for laboratory personnel, it has been proposed to introduce "unconditioned" air from an auxiliary source across the open hood face so that the unconditioned air may be indrawn through the test area by the hood exhaust system without imposing a drain on the "conditioned" air in the laboratory room. Heretofore, attempts to accomplish this have not been successful. Designers have been confronted with the following dilemma: If auxiliary air is discharged in the usual fashion from each side of the hood face at a velocity sufficient to "carry" to the center of the face, the concentration of air at this point results in turbulence and an air velocity over the work area far in excess of the desirable 100 feet per minute. If the velocity of the auxiliary air is reduced, only the edges of the hood face are blanketed or "curtained" by unconditioned air, and the center of the hood face continues to draw in conditioned air from the laboratory.

Therefore, it is an object of the invention to provide a fume hood ventilating method and apparatus effective to maintain a uniform air intake velocity at a desirable level across the entire front of the open hood face which prevents the hood exhaust system from drawing in air from the room in which the hood is located, resulting in a substantial saving of conditioned air and permitting operation of a large number of hoods in a laboratory of limited size. It is another object to provide a scheme of

2

hood ventilation which not only provides freedom from fumes but which enables the technician to work in more comfortable, even-tempered surroundings in all seasons of the year.

It is an object related to the above to provide a method and apparatus of the described character that permits selective operation of any number of fume hoods in a room without requiring adjustment of the room air conditioning system in order to maintain room temperature and secure a proper air intake velocity across the hoods in operation.

With more particularity, it is an object to provide a fume hood ventilating apparatus for discharging a plurality of adjacent, curtain-like air streams across an open hood face at predetermined relative velocities so that air is supplied without turbulence across the entire open face of the hood, in order that the hood exhaust system may be effectively operated without substantial drawing of air from the room in which the fume hood is located.

It is another, more detailed object to provide a fume hood ventilating method and apparatus as characterized above which develops and discharges a plurality of adjacent air streams having predetermined incremental velocities from a common source of static air pressure.

It is a related object to provide an apparatus of this type that is exceptionally economical to construct in that no complicated valves or nozzles are relied upon.

It is a further object to provide a fume hood ventilating method and apparatus readily adapted for use with conventional hoods and which may be utilized with existing installations.

Other objects and advantages of the invention will become apparent upon reading the attached detailed description and upon reference to the drawings, in which:

FIGURE 1 is a perspective view, partially diagrammatic, of a laboratory fume hood incorporating a ventilating apparatus embodying the present invention.

FIG. 2 is a side view of the hood and ventilating structure shown in FIG. 1.

FIG. 3 is a perspective, fragmentary view, partially broken away, of a portion of the ventilating structure shown in FIG. 1.

FIG. 4 is a fragmentary, horizontal section taken along line 4—4 in FIG. 1.

FIG. 4a is a diagrammatic perspective of the air streams appearing in FIG. 4.

FIGS. 5 and 6 show alternate patterns for the air valve plate shown operably positioned in FIG. 3.

FIG. 7 is a section similar to FIG. 4, but showing an alternative air-discharge arrangement.

FIG. 8 is a perspective view showing the alternative valve plate structure appearing in FIG. 7.

While the invention will be described in connection with preferred embodiments and procedures, it will be understood that I do not intend to limit the invention to those embodiments and procedures. On the contrary, I intend to cover all alternatives, modifications and equivalents as may be included within the spirit and scope of the invention as defined by the appended claims.

Turning now to the drawings, there is shown a laboratory working area in the form of a table top 10 on which a fume hood 11 is mounted. The hood 11 includes a back panel 12, opposite lateral side panels 13 and 14, and a top panel 15 having a downwardly sloping front portion

16. The hood thus surrounds the top and three sides of the table top 10 and leaves an open hood face 17 which provides access to the working area.

For withdrawing objectionable gases from within the hood, an exhaust system 18 is coupled to the hood 11 by an exhaust duct 19 which opens into the hood through the top panel 15. With the exhaust system 18 in operation, gases within the hood 11 are continuously withdrawn through the duct 19 and replaced by air entering through the open hood face 17.

In accordance with the invention, a plurality of adjacent, curtain-like streams of air are discharged across the open hood face 17 from one of its edges, the streams having progressively-varying velocities with the outermost stream velocity being the highest, so that air is uniformly supplied, without turbulence and at low velocities, across the open hood face throughout the flow of the combined air streams. In this way, the exhaust system 18 is prevented from drawing in "conditioned" outside air through the open face 17 but is able to control and maintain a steady, low velocity air current over the table top 10. In the present embodiment, three curtain-like streams A, B and C, (see FIGS. 4 and 4a) are discharged across the open hood face 17 from each opposed lateral edge of the face. The outermost stream C is given a velocity effective to carry the air to approximately the centerline of the table top 10; the middle stream B is given a velocity sufficient to carry it to the intermediate portion of the hood face, and the rear stream A is given a velocity sufficient to carry only to the side or near portion of the face 17. Therefore, each set of curtain-like air streams A, B and C, completely blankets one-half of the open hood face 17.

Because of the progressively-varying velocities of the adjacent air streams A, B and C, with the outermost stream C being the fastest, it may be seen that each stream provides air to adjacent lateral portions of the hood face, and therefore the supply of air is substantially uniform over the entire hood face 17. More specifically, each air stream, A, B and C, supplies air directly and without turbulence to the adjacent areas 17a, 17b and 17c of the hood face 17 (FIG. 4a) so that the entire open face is blanketed.

In a practical case, it will be assumed that an average air velocity over the work area of 100 feet per minute is desired. This is established by operating the exhaust system 18 so that it moves 100 cubic feet of air for each square foot of open hood face. Under such conditions, and with a work table 6-7 feet long, it has been found that satisfactory operation results when the air velocity of stream A is approximately 200 feet per minute, the velocity of stream B is approximately 350 feet per minute and the velocity of stream C from 600 to 800 feet per minute. The exhaust system 18 will then curve the streams A, B and C inwardly through the open hood face 17 to create an air intake velocity over the table 10 of 100 feet per minute. It will be understood that the streams A, B and C curve solely under the influence and control of the exhaust system 18. Thus, the initial discharge velocities of the streams merely position the air so that it may be drawn into the hood at the proper velocity by the exhaust system. In this way, the air moves through each of the hood face areas 17a, 17b and 17c at substantially the same velocity and in the same quantity, i.e. the air flow uniform across the entire hood face 17.

In order to provide the curtain-like air streams mentioned above, a ventilating apparatus 20 is utilized having an air supply duct 21, air supply chambers 22 and 23, and an air supply system 24 for maintaining a static air pressure in the chambers 22 and 23. The air supply system 24 feeds air through the duct 21 and builds up the required discharge pressure in the supply chambers 22 and 23. The air supply chambers are provided with opposed, vertically aligned discharge ports 25 and 26, respectively, and sets of deflectors 27, 28 (see FIG. 3) are

utilized to insure an even supply of air throughout the vertical length of the discharge ports 25, 26.

In keeping with one aspect of the invention, the plurality of adjacent, curtain-like streams of air A, B and C, having progressively-varying velocities are developed and discharged from a single source of static pressure, that is, the air supply chamber 22, by venting equal volumes of air from the source of static pressure through discharge chambers of progressively-varying width but equal length. Since three streams of air are discharged from the air supply chamber 2, three adjacent discharge chambers, 22a, 22b and 22c, are provided, with the outermost chamber 22c being the narrowest. It will be appreciated that a given volume of air under a constant pressure will flow more rapidly, that is, at a higher speed as measured in feet per second, through a narrow chamber than through a wide one, assuming the chambers to be of equal height as in the present case, and therefore the discharge velocities of the equal volumes of air vented into the chambers 22a-22c are inversely proportional to the width of the chambers. By making the discharge chambers of progressively-varying width, with the narrowest at the outside, the desired air stream velocities are obtained.

In the preferred embodiment, the chambers 22a-22c are formed by subdividing a portion of the air supply chamber 22 by positioning wall plates 31, 32 behind the vertical discharge port 25 and within the chamber 22.

In order to introduce equal volumes of air per unit of time uniformly into each of the chambers 22a-22c, a valve plate structure 33 is disposed between the discharge members and the air supply chamber 22. The valve plate structure 33 is provided with different patterns of openings permitting equal volumes of air to flow from the region of static pressure within the air supply chamber 22 to the respective air discharge chambers 22a-22c. In the preferred embodiment, the valve plate 33 is a unitary structure extending across the chamber 22 and abutting the rear edges of the wall plates 31, 32. The valve plate thus comprises three portions 33a, 33b and 33c, which control the flow of air to the chambers 22a, 22b, and 22c, respectively.

Equal volumes of air per minute are vented through the valve plate portions 33a-33c to the respective air discharge chambers by providing openings in the valve plate proportioned so that the total opening area in each of the valve plate portions is identical. In this way, an equal volume of air per unit of time will flow through the openings in the valve plate portions 33a-33c under the static pressure in the air supply chamber 22 into the respective air discharge chambers.

In order to keep the open areas in each of the valve plate portions 33a-33c equal when the width of these portions varies, while maintaining uniform air flow through the entire plate area, a different pattern of openings is cut into each of the plate portions. In the FIG. 5 embodiment, the portion 33c is provided with evenly-spaced large openings; the portion 33b provided with evenly-spaced intermediate-size openings, while the portion 33a is provided with a plurality of evenly-spaced openings. By correctly sizing the openings in each of the plate portions, an approximately equal amount of open space in each of the plate portions can easily be achieved, with the result that an equal volume of air per minute will flow through the openings in each of the plate portions. Since the openings in each plate portion are symmetrically spaced, the flow of air therethrough will be substantially uniform.

Alternatively, a valve plate 34, made up of plate portions 34a, 34b and 34c having openings of equal size, can be utilized in lieu of the valve plate 33 (see FIG. 6). The valve plate 34 is equivalent to the valve plate 33 discussed above and may be substituted therefor in the apparatus 20.

In order to keep the open area in each of the valve plate portions 34a-34c approximately equal, the open-

ings are spaced progressively closer together, with the openings in 34a being substantially farther apart than in the portion 34c. In each of the valve plate portions 34a-34c, the openings are symmetrically located so that the flow of air therethrough will be uniform throughout the plate area. It will be appreciated that by properly spacing the equally sized openings in the respective valve plate portions 34a-34c, an equal open area can be achieved in each of the plate portions despite the differences in their width. Thus, a constant volume of air per minute will flow through each of the portions 34a-34c.

In keeping with an alternative aspect of the invention, the plurality of adjacent curtain-like streams of air A, B and C having progressively-varying velocities may be developed and discharged from a single source of static pressure, that is, the air supply chamber 22, by venting progressively-varying volumes of air from the pressure source through adjacent discharge chambers of substantially equal size (see FIGS. 7 and 8). In this embodiment, parts corresponding to those already discussed have been given identical identifying numerals with the value "100" added thereto.

In the alternative embodiment, an air supply chamber 122 is provided with vertically-aligned discharge ports 125 and wall plates 131 and 132 which define air discharge chambers 122a, 122b and 122c. A valve plate 133 is interposed between the air supply chamber 122 and the respective air discharge chambers 122a-122c.

As stated above, the air discharge chambers 122a-122c are of substantially equal size. To provide a progressive variation in air discharge velocity from the respective chambers, progressively-varying amounts of air are vented through the valve plate 133 into each of the chambers. For this purpose, adjustable venting ports 41, 42 and 43 are provided. Preferably, the venting ports 41-43 have a height substantially equal to the height of the air discharge ports 125, but they are of varying widths so that progressively-increasing volumes of air are admitted to the air discharge chambers 122a, 122b and 122c, in that order.

In order to adjust the width of the venting ports 41-43, the valve plate 133 is provided with a pair of shutter-like doors 45 for each of the ports. It will be apparent that by adjustably swinging these doors about their hinged connections with the valve plate, the effective apertures of the ports 41-43 can be adjusted so that the proper volumes of air will be vented to the air discharge members 122a-122c. In this way, the desired, progressively-variable, air velocities in the curtain-like streams 100a-100c can be easily obtained.

I claim as my invention:

1. In a laboratory fume hood having an open hood face lying in a plane dividing the interior of the hood from the outside room and an air exhaust system for the interior of the hood, a ventilating apparatus for preventing the air exhaust system from drawing conditioned room air through the plane of the hood face comprising, in combination, an air supply chamber positioned on the room side of said plane and having a wall extending from said plane adjacent one edge of said open hood face, an air supply system for maintaining a static air pressure in said chamber, said wall having a plurality of adjacent, elongated air discharging ports extending from end to end of said hood face edge and opening into said chamber for directing adjacent, curtain-like streams of air from said chamber parallel to said plane and over a portion of the hood face, and means interposed between said chamber and said ports for causing the air streams discharged from the latter to have progressively-varying velocities with the outermost stream being the fastest, said streams thus blanketing said hood face portion with uniformly moving air from said supply system.

2. In a laboratory fume hood having an open hood

face lying in a plane dividing the interior of the hood from the outside room and an air exhaust system for the interior of the hood, a ventilating apparatus for preventing the air exhaust system from drawing conditioned room air through the plane of the hood face comprising, in combination, a pair of air supply chambers positioned on the room side of said plane, said chambers having walls extending from said plane adjacent opposite lateral edges of said open hood face, an air supply system for maintaining a static air pressure in said chambers, said walls having pluralities of adjacent, elongated air discharging ports extending from end to end of said hood face edges and opening into respective ones of said chambers for directing adjacent, curtain-like streams of air from said chambers parallel to said plane and over adjacent portions of the hood face, and means interposed between said chamber and said ports for causing the air streams discharged from the latter to have progressively-varying velocities with the outermost stream from each chamber being the fastest and having a velocity sufficient to carry midway across the hood face so as to meet the opposed outermost air stream, said streams thus blanketing the entire open hood face with uniformly moving air from said supply system.

3. In a laboratory fume hood having an open hood face lying in a plane dividing the interior of the hood from the outside room and an air exhaust system for the interior of the hood, a ventilating apparatus for preventing the air exhaust system from drawing in conditioned room air through the plane of the hood face comprising, in combination, an air supply chamber positioned adjacent one edge of said open hood face, an air supply system for maintaining a static air pressure in said chamber, a plurality of adjacent, elongated air discharge chambers positioned on the room side of said plane and having adjacent walls extending from said plane at one edge of said open hood face, each of said walls having adjacent, elongated air discharging ports extending from end to end of said hood face edge and opening into the respective air discharge chambers for directing adjacent, curtain-like streams of air from said chambers parallel to said plane and over a portion of the hood face, said discharge chambers being of progressively varying widths with the outermost chamber being the narrowest, and means for directing substantially equal amounts of air per unit of time from said supply chamber to each of said discharge chambers so that the air streams discharged from the latter have progressively varying velocities with the outermost stream being the fastest, said streams thus blanketing said hood face portion with uniformly moving air from said supply system.

4. In a laboratory fume hood having an open hood face lying in a plane dividing the interior of the hood from the outside room and an air exhaust system for the interior of the hood, a ventilating apparatus for preventing the air exhaust system from drawing in conditioned room air through the plane of the hood face comprising, in combination, an air supply chamber positioned adjacent one edge of said open hood face, an air supply system for maintaining a static air pressure in said chamber, a plurality of adjacent, elongated air discharge chambers positioned on the room side of said plane and having adjacent walls extending from said plane at one edge of said open hood face, each of said walls having adjacent, elongated air discharging ports extending from end to end of said hood face edge and opening into the respective air discharge chambers for directing adjacent, curtain-like streams of air from said chambers parallel to said plane and over a portion of the hood face, said discharge chambers being of substantially equal size, and means for directing progressively varying amounts of air from said supply chamber to said discharge chambers with the outermost chamber receiving the greatest air volume so that the air streams discharged from the discharge chambers have progressively varying velocities with the outer-

most stream being the fastest, said streams thus blanketing said hood face portion with uniformly moving air from said supply system.
